MEANS FOR CONTROLLING STARTING MOTOR AND IGNITION CIRCUITS

Filed June 9, 1930

UNITED STATES PATENT OFFICE

2,032,775

MEANS FOR CONTROLLING STARTING
MOTOR AND IGNITION CIRCUITSHerbert H. Trail, Vancouver, British Columbia,
Canada, assignor to Motor Devices, Inc., Chi-
cago, Ill., a corporation of Illinois

Application June 9, 1930, Serial No. 459,912

2 Claims. (Cl. 200—14)

This invention relates to improvements in means for controlling starting motor and ignition circuits and it consists of the matters herein-after described and more particularly pointed out in the appended claims.

The primary object of the invention is to provide an improved means of this kind, which is so constructed as to simplify the manual manipulation thereof to obtain desired results.

10 A further object of the invention is to provide an improved means of this kind, which is so designed to simplify the construction thereof.

Still a further object of the invention is to provide an automatic means for controlling a starting motor circuit, and a simplified means for manually controlling said circuit should the automatic means fail.

These objects of my invention as well as others, together with the many advantages thereof, will appear as I proceed with my specification.

Referring to the drawing which will illustrate by way of example, convenient forms of the invention:—

Fig. 1 is a view partly in elevation and partly in longitudinal section of a coil unit part of my improved means for controlling starting motor and ignition circuits.

Fig. 2 is a transverse sectional view through the coil unit taken on the line A of Fig. 1.

30 Fig. 3 is a transverse vertical view through the coil unit as taken on the line B of Fig. 1.

Fig. 4 is a perspective view of some of the component parts of the coil unit.

35 Fig. 5 is a diagrammatic view of my improved means for controlling starting motor and ignition circuits.

Fig. 6 and Fig. 7 are diagrammatic views of a manually operated switch shown in Fig. 5, illustrating the operated parts in their various relative positions.

Referring now to that embodiment of the invention illustrated in the accompanying drawing and more particularly to Figs. 1, 2, 3, and 4 thereof, 1 indicates as a whole, an ignition coil and a manually operated switch adapted to control the coil circuit also a circuit arranged to control the starting motor circuit of an internal combustion engine. 2 is a cylindrical metal shell for enclosing the ignition coil and circuit wires, 3 is a cap formed of insulating material supporting the terminals 23, 24, 25 and two not shown, and arranged to close one end of the cylinder shell 2. The other end of said shell is closed by the metallic disc 4 formed with the extension 5 for

suitable attachment to the instrument board of an automobile.

A lock plug 6 is mounted for rotary movement within the extension 5 and is manually operated by the key 22 and is prevented from unauthorized operation by removal of the key. A fiber disc 7 is secured to the lock plug 6 by the screw 10 for supporting and insulating a contact member 8. Recesses 18 are formed in the periphery of the fiber disc 7 for receiving the arms 17 of the contact member 8 and are much wider than the width of the arms 17 so as to permit of the disc 7 being partially rotated relative to the contact member 8 when said parts are in their relative assembled position as shown in Fig. 1. A spring 11 is positioned between the disc 7 and the contact member 8, and one end of the spring fits in a hole in the disc and the other end fits in a hole in the contact member. This spring permits biasing the contact member 8 at one end of its limited rotary movement within the recesses 18 of the disc, and permits biasing the contact member away from the disc 7 and towards the insulating disc 12 which is supported from the metal shell 2. The contact arm 9 is secured to the lock plug 6 by the screw 10 before mentioned thereby making a unit component of the lock plug 6, the fiber disc 7 and the contact arm 9. The insulating disc 12 supports the contacts 13, 14, 15, and 16 which are arranged in circuit with the ignition coil and a circuit for controlling a starting motor circuit. The contacts 21 of the contact member 8 are arranged in the path of the stationary contacts 13, 14, and 15 of the insulating disc 12, so as to engage therewith while the contact arm 9 is arranged in the path of the stationary contact 16 of the insulating disc 12 so as to engage therewith. The stop arm 26 is formed on the contact member 8 and is arranged to coact with the stop pins 28 to limit the rotary movement of the contact member 8. While the stop pins 28 limit the rotary movement of the contact member 8 they do not limit the movement of the contact arm 9 which can be moved a further distance, amounting to the difference between the width of the arms 17 of the contact member 8 and the width of the recesses 18 of the fiber disc 7. This further movement of the contact arm 9 is indicated at 71 in Fig. 3 which shows the amount of movement of the contact arm 9 relative to the contact member 8.

Referring now particularly to Figs. 5, 6, and 7 of the drawing, which shows diagrammatically, my improved means for controlling starting motor and ignition circuits. 29 and 30 represent the primary and secondary windings of the ig-

nition coil. 46, 46, 47, 48, and 49 represent the terminals situated in the cap 3 of Fig. 1. 52 is the flywheel of the engine 64. 38 is the ignition timer and 50 the ignition distributor, the leads 51 going to the spark plugs of the engine.

5 The starting motor 54 has attached to it a mechanical starting device including a pinion 57 which is caused to be moved axially into and out of engagement with the toothed ring gear 53. A 10 contact ring 55 is secured to the pinion 57 and moves into and out of contact with the contact arm 58 in circuit with the electro-magnet 42 which is arranged to operate the contacts 63 of the starting motor circuit. 32 is an electric storage 15 battery. S represents a manually operated switch having a stationary insulating disc 12 to which are secured the stationary contacts 13, 14, 15, 16, and the rotating contact member 8, and the rotating contact arm 9 which is manually 20 actuated by the lock plug 6. The movement of the contact member 8 is limited by the stop arm 26 coacting with the stops 28. The contact arm 9 is insulated from the contact member 8 and is caused to actuate the contact member 8 by an 25 extension contacting with the projection 65a of the contact member 8 when moved in one direction, and by said extension coacting with the spring 11 and the projection 65 when moved in another direction. In this manner, manual operation 30 of the lock plug 6 can be caused to rotate both the contact member 8 and the contact arm 9 together and when the contact member 8 has been rotated the limit of its movement a further rotary movement can be imparted to the contact arm 9 by compressing the spring 11 by a 35 further movement of the lock plug 6. Figure 7 shows the switch components in their relative "off" position. In Fig. 5 the switch is shown with its component parts in their normal "on" position. Fig. 6 shows the switch components in their relative position when the ignition circuit 40 would be energized and a circuit controlling a starting motor circuit has been established.

Assuming that the engine is stationary, when 45 the switch component parts would be in their relative positions as shown in Fig. 7, and it desirous of starting the engine; manual movement of the key 22, or the lock plug 6, in a clockwise direction causes both the contact arm 9 and the contact member 8 to be rotated in a similar direction until the stop arm 26 contacts with the stop 28. Rotary movement of the contact member 8 is then arrested and the parts are in their relative positions as shown in Fig. 5, when the projections 21 50 contact with the stationary contacts 13, 14, and 15. Further manual movement of the key 22, or the lock plug 6 in a clockwise movement, causes the contact arm 9 to contact with the stationary contact 16, and in so doing the spring 11 is compressed.

The component parts of the switch are only maintained in their relative positions as shown in Fig. 6 just so long as the operator manually holds the key 22 or the lock plug 6 at the maximum limit 65 of its clockwise travel, and immediately the operator releases the key the spring 11 causes the contact arm 9 to be rotated in an anti-clockwise direction and out of contact with the stationary contact 16.

70 When the operator actuates the switch from its "off" to its "on" position, the switch parts move from the position shown in Fig. 7 to the position shown in Fig. 6, and upon releasing the operating member such as the key 22 or the lock plug 6, the switch parts automatically move to

the relative positions as shown in Fig. 5, which would be the normal "on" position of the switch while the engine is running. It is thus seen that, when the switch is actuated in the usual manner to its "on" position, the contact arm 9 only momentarily contacts with the stationary contact 16, while the contact member 8 is moved into contact with the stationary contacts 13, 14, and 15 and is maintained in such a position until the switch is manually actuated in an anti-clockwise direction 10 to its "off" position.

Thus when the switch is actuated to its "on" position, the contact member 8 is actuated into contact with the stationary contacts 13, 14, and 15 thereby energizing the ignition circuit of the 15 engine by way of battery 32 lead 33 terminal 47 lead 34 stationary contact 15 contact member 8 contact 14 primary winding 29 lead 35 terminal 48 lead 37 timer 38 and to ground at 39 thereby causing secondary current to be transmitted to the engine by way of the secondary winding 30 terminal 49 lead 62 distributor 50 and the leads 51. The contact arm 9 is also moved into contact with the stationary contact 16, momentarily, thus energizing the electro-magnet 42 to energize 25 starting motor circuit by way of battery 32 lead 31 lead 33 terminal 47 lead 34 stationary contact 15 contact member 8 stationary contact 13 lead 40 terminal 46 lead 41 electro-magnet 42 lead 43 terminal 44 lead 45 stationary contact 16 contact 30 arm 9 and to ground at 61. Upon the electro-magnet 42 becoming momentarily energized it is caused to close the contacts 63 thus energizing the starting motor circuit by way of battery 32 lead 31 lead 59 contacts 63 and to ground by way 35 of lead 60.

Upon the starting motor being energized the pinion 57 and the contact ring 55 move axially into driving engagement with the flywheel ring gear 53 which in turn rotates the engine. The axial movement of the pinion and contact ring 55 causes it to contact with the contact arm 58. By this time the circuit which primarily energized the electro-magnet 42 is opened by the contact arm 9 being actuated by the spring 11 45 out of contact with the contact 16 and the electro-magnet 42 is maintained energized by way of battery 32 leads 31 and 33 terminal 47 lead 34 contact 15 contact member 8 contact 13 lead 40 terminal 46 lead 41 electro-magnet 42 50 lead 56 contact arm 58 contact ring 55 and to ground at 60. In this manner the electro-magnet is maintained energized to keep the contacts 63 closed and the starting motor energized until such time as the engine runs under its own 55 power. At this time the ring gear 53 causes the pinion 57 to overrun the speed of the starting motor whereupon the pinion moves axially out of driving engagement with the ring gear. This also moves the contact ring 55 out of contact 60 with the contact arm 58 thereby de-energizing the electro-magnet which causes the spring 69 to de-energize the starting motor by opening the contacts 63.

Should the engine stall while the switch is in its normal "on" position as shown in Fig. 5 manual actuation of the key 22 or the lock plug 6, slightly in a clockwise direction compresses the spring 11 and moves the contact arm 9 into contact with the stationary engagement 16 thereby causing the starting motor to be again energized in the manner heretofore described. When the operator releases the key 22 or the lock plug 6, the spring 11 is caused to bias and move the en- 70 75

gagement arm 9 out of contact with the stationary contact 16 to the position shown in Fig. 5.

In the arrangement of the invention heretofore described, the de-energizing of the starting motor circuit is automatic in its action, excepting when the operator purposely actuates the switch from its "on" to its "off" position when the component parts are actuated to the position as shown in Fig. 7 which causes the de-energizing of both the ignition and starting motor circuits.

To simplify the construction and to eliminate the automatic de-energizing of the starting motor circuit should it be so desired, the lead 56 and the contact arm 58 may be eliminated, in which case it would be necessary for the operator to overcome the resistance of the spring 11 to hold the contact arm 9 in contact with the stationary contact 16 to maintain the starting motor energized till the engine runs under its own power. Upon the operator releasing the key 22 or the lock plug 6 the spring 11 would bias and actuate the contact arm 9 out of contact with the stationary contact 16 hereby de-energizing the starting motor circuit without any effort on the part of the operator.

By the construction described I am enabled to control by a single manual operation, both the starting motor circuit and the ignition circuit of an internal combustion engine, and should the engine stop of itself, it can again be started by merely applying a slight movement to the manually operated member in the same direction that is necessary to primarily energize the starting motor and ignition circuits.

While in describing the invention, I have referred in detail to the form, arrangement and construction of the parts employed, the same is to be considered merely as illustrative so that I do not wish to be limited thereto except as may be specifically set forth in the appended claims.

I claim as my invention:—

1. A switch embodying therein a plurality of

fixed contacts, a contactor turnable in one direction from its "off" to its "on" position and wherein it engages one of said fixed contacts, a second contactor turnable in said one direction from its "off" to its "on" position wherein it engages the others of said contacts, yieldable means between said contactors operating when the first contactor is manually turned in said one direction into its "on" position, to cause the second contactor to turn in the same direction into its "on" position, said yieldable means operating when said first contactor is released, to turn it in the other direction partway toward its "off" position wherein it is disengaged from said one of said contacts, and means on said second contactor for stopping the first contactor in its last mentioned position and positively connecting both contactors together for a joint return to the full "off" position, when said first contactor is manually moved back to its full "off" position.

2. A switch embodying therein a plurality of fixed contacts, a contactor turnable in one direction from its "off" to its "on" position and wherein it engages one of said fixed contacts, a second contactor turnable in said one direction from its "off" to its "on" position wherein it engages the others of said contacts, stops for determining the "off" and "on" positions of said second contactor, yielding means between said contactors operating when the first contactor is manually turned in said one direction to its "on" position to cause the second contactor to turn in the same direction into its "on" position, said yieldable means operating when first contactor is released, to turn it in the other direction partway toward its "off" position wherein it is disengaged from said one of said contacts, and means on said second contactor for stopping the first contactor in its last mentioned position and positively connecting both contactors together for a joint return to the full "off" position, when said first contactor is manually moved to its full "off" position.

HERBERT H. TRAIL.
